UNITED STATES PATENT OFFICE.

PHILO P. STEWART, OF TROY, NEW YORK.

STOVE.

Specification forming part of Letters Patent No. 23,622, dated April 12, 1859; Reissued May 17, 1864, No. 1,673.

To all whom it may concern:

Be it known that I, PHILO P. STEWART, of Troy, in the State of New York, have invented certain new and useful Improvements in Cooking-Stoves; and I do hereby declare that the following is a full, clear, and exact description thereof, reference being had to the accompanying drawings, making part of this specification, in which—

10 Figure 1 is a side elevation; Fig. 2, a longitudinal vertical section; Fig. 3, a cross vertical section taken at the line A, *a*, of Fig. 2; and Fig. 4, a horizontal section taken at the line B, *b*, of Fig. 2.

15 The same letters indicate like parts in all the figures.

My said invention relates to improvements on what is known as the return flue stove in which the fire chamber is placed in front of the oven, and the products of combustion pass in a sheet between the top boiler plate of the stove and the top of the oven, and dividing pass down two side flues at the back, thence in a single sheet under 20 the oven, around the front end of a flue plate, back between this plate and the bottom plate of the oven, and up to the exit pipe through a rising flue at the back of the oven, and between the two descending flues, 25 there being a passage directly from the top flue over the upper end of the back rising flue, and controlled by a damper, for the purpose of discharging the products of combustion directly to the chimney when it may 30 be desired not to heat the oven, as in kindling the fire.

Stoves of this class although presenting many advantages, have been defective on account of the difficulty of imparting a uniform heat to the four sides of the oven. As 40 the fire chamber is directly in front of the oven, and the products of combustion pass directly from the fire chamber in a single sheet over the top of the oven, and thence to the back and bottom, it follows that the back and bottom receive less heat than the front and top. This inequality has been in part remedied by an air space between the fire back and the front oven plate, and by 45 lining the top oven plate and by other devices; but all these have so far proved to be only partial remedies, and while they have tended to equalize the temperature, have been wasteful of fuel.

I have found by repeated experiments 55 that whatever heat is imparted to the back rising flue, which is immediately connected with the exit pipe leading to the chimney, is mostly wasted by being carried directly out into the chimney, and this is partly true 60 also of the return flue at bottom; and the leading object of my said improvements is to prevent the heat while passing through the direct flues from striking through to the return flues, and thereby preserving it for 65 the purposes of heating the oven.

In the accompanying drawings (*a*) represents the fire chamber in front, and (*b*) the oven, the rear part of which is back of the fire chamber, and the front part extending under the fire chamber, so that the front part of the oven receives heat from the back and from the bottom of the fire chamber. At the back of the oven there are three vertical flues side by side, the two side ones (*c*, *c*) being diving flues, and the one in the middle (*d*) being a rising flue leading to the exit pipe. The products of combustion pass directly from the fire chamber in a single sheet over the top of the oven, and, 70 dividing, descend through the two flues (*c*, *c*) at the back, and at the bottom unite in a single sheet in the flue space (*e*) which extends the whole length of the bottom of the oven. The space between the bottom plate (*f*) of the oven, and the bottom plate (*g*) of the stove, is separated into a direct flue (*e*) and a return flue (*h*) by an inclined plate (*i*) the front end of which is higher than the rear end that the capacity of the 75 flue space (*e*) may be gradually reduced toward the front end of the oven the better to concentrate the action of the products of combustion against the bottom of the oven as they are reduced in temperature by traveling from the fire chamber. The upper surface of this plate is cast with inclined flanches to form dove tail recesses to hold any suitable kind of earthy cement which is to be plastered over, to act as a nonconductor, and prevent the heat from striking through the plate to the return flue (*h*) below and thereby preserve it for directly heating the bottom of the oven. The front 80 end of the inclined plate (*i*) does not extend entirely to the front plate (*j*) of the stove, sufficient space being left there for the passage of the products of combustion 85

down into the return flue (*h*) the rear end of which communicates with the rising flue (*d*) leading to the exit pipe.

The partitions (*k*, *k*) which separate the two descending flues (*c*, *c*) from the rising flue between them, are made double with the space between filled in with cement or other nonconducting substance to prevent

the heat in the flues (*c*, *c*) from striking 10 through to the rising flue. And the back oven plate opposite the rising flue (*d*) is also made double as at (*v*) and the space between filled in with cement or other nonconducting material so that the heat applied to this plate by the heated products of combustion in the descending flues (*c*, *c*) and which is spread through the entire back plate of 15 the oven by conduction, shall not strike through to the rising flue and be thereby

20 wasted.

The top flue above the oven at the back end communicates directly with the upper end of the rising flue (*d*) by an aperture controlled by a damper (*m*) which when 25 closed directs the draft around the oven in the manner above described. And to prevent the heat from striking through this damper to the rising flue, when the aperture is closed and thereby wasting heat, this 30 damper is made double and filled in with cement or other nonconductor. In this way and by the means above described I am enabled not only to equalize the heat around the oven, but to accomplish this result with 35 less fuel than by any other plan known to me.

The stove is extended back of the back flues as at (*n*) to form a chamber (*o*) in which articles can be kept warm, and to 40 form above this a chamber (*p*) into which the bottom of a boiler (*q*) extends. The

rising flue (*d*) discharges the gaseous products of combustion into this chamber, from whence they escape through to flues in the boiler to the exit pipe above the boiler, but 45 this makes no part of the invention claimed in this application.

If desired the bottom of the stove which forms the bottom flues may be encased as at (*r*) to prevent the escape of heat into the 50 room.

What I claim as my invention and desire to secure by Letters Patent is—

1. The method substantially as described, of preventing the heat from striking through 55 to the rising flue leading to the chimney by separating it from the back oven plate, and from the two descending flues by nonconducting partitions or the equivalents thereof as described and for the purpose set 60 forth.

2. I also claim in combination with the flue above the oven and with the rising flue leading to the chimney, the employment of a double damper filled in with cement or 65 other equivalent non-conducting material, substantially as described to prevent the heat from striking through from the top flue to the rising flue, as set forth.

3. And I also claim separating the direct 70 flue under the oven from the return flue below by means of a plate lined with cement, or rendered non-conducting by equivalent means, substantially as described, to prevent the heat from striking through to the return 75 flue, and thereby impart greater heat to the bottom of the oven, as set forth.

P. P. STEWART.
